UNITED STATES PATENT OFFICE.

RAYMOND F. BENNETT, OF PORTLAND, MAINE.

BOOM-POINT FOR DERRICKS.

No. 856,212.

Specification of Letters Patent.

Patented June 11, 1907.

Application filed January 2, 1907. Serial No. 350,843.

To all whom it may concern:

Be it known that I, RAYMOND F. BENNETT, a citizen of the United States of America, and a resident of Portland, Maine, have 5 invented certain new and useful Improvements in Boom-Points for Derricks, of which the following is a specification.

My invention relates to the construction of derrick of that class where an inclined 10 boom is pivoted at its base and is supported at various positions by a topping lift, the supporting tripod being stationary and the load being handled by a single line or "whip." In such derricks the fall is commonly led to 15 a block carried by the load bail which is suspended from the end of the boom and thence it leads through a snatch block located on one or the other side of the boom at its foot and thence upward to a block suspended from 20 the tripod. This arrangement is efficient when the boom is to be swung toward the side on which the snatch block is located but when it is swung the other way, the snatch block has to be changed to the other side of 25 the boom and the fall has to be drawn over the boom causing much friction and interfering with the operation of the derrick.

The object of my invention is to provide a boom point in which the sheave or sheaves 30 will guide the fall vertically over the end of the boom and lead it down to the base of the boom suspending the block in such a way that both parts of the line may have a limited side lead. I accomplish this object by 35 hanging at the end of the boom one or more blocks for guiding the fall, the upper edge of the upper sheave being located above the line of the upper surface of the boom and the block or blocks being so hung that they 40 will take the plane of the two parts of rope adjacent to the sheave when there is a limited amount of side lead in either direction from the boom point.

I illustrate my invention by means of the 45 accompanying drawing in which

Figure 1 is a diagrammatic view of a derrick as it would appear on a lighter and provided with a boom point constructed according to my invention. Fig. 2 is a front view of the 50 same with the boom cut away, Figs. 3 and 4 are side view and plan respectively of the preferable form of my invention. Fig. 5 is a sectional detail thereof, Figs. 6 and 7 are side view and plan respectively of an alter- 55 nate form of my invention.

In Figs. 1 and 2 *i* represents the side legs,

h the back leg, *j* and *j* the cross member of a derrick tripod. The boom *g* is shown supported by the topping lift tackle *x* and is hinged and pivoted to the deck at its lower 60 end as in common practice. *y y* are eye bolts fastened to the deck situated at either side and a little in front of the foot of the boom. 11 is a sheave block suspended to the cross member *j* and 10 is a sheave block provided 65 with a swivel hook and adapted to engage either of the eye bolts *y y*. *z* is the winding drum used in hoisting, *w* is a guy attached near the outer end of the boom and leading to one side and is used for preventing the 70 boom from swinging too far and is usually tended by hand.

My invention has its best use in the derrick of a lighter when the loads are handled with a single line (called "single whip" or 75 simply "whip.") The parts so far described are common and well known in derricks of this class and need no further description.

Referring now particularly to Figs. 3, 4, and 5, there is seen the frame *f* attached to 80 and extending beyond the boom *g* and forming a part thereof. The frame *f* curves upward toward the outer end and with an outer end plate *f'* uniting the extremities of the side plates. Through the end plate is passed 85 the swivel eye bolt *a*, holding this eye bolt in place is the washer *c* and the key *d*, the washer *c* being rabbeted on its top side for key *d*. Through the eye of this eye bolt is passed the bent pin 3 which hangs loosely 90 thereon. From this pin is hung the block composed of the shell members *e e*, the filler *k*, the sheave 7 and the sheave pin 2. The pin 3 is bent so as to insure that the block will hang concentrically with the eye bolt, 95 and the attachment of the block with the eye bolt is thus very loose so as to allow lateral swinging of the block. This attachment of the block to the frame is made as short as possible. This attachment allows the swinging 100 of the block two ways and the swiveling of the block about the eye bolt allows the sheave to take up a position in the plan of the two parts of the rope which reach the sheave and allow these two parts to have considerable side lead both one way or in opposite ways.

Referring to Fig. 1 in connection with the construction above described there is shown the topping lift bail *b* to which is attached the 110 topping-lift tackle *x* as in usual practice, and attached to the boom by the pin 1. From

this pin 1 is also hung the load bail b' from which is hung the hoisting tackle when one is used, the fall passing up over the sheave 7 and thence to the winding drum z as in the 5 case of the single whip. The sheave 7 is so proportioned and supported that when in its lowest position as shown in full lines, the rope r will run clear of the top of the boom, and when in its highest position as shown in 10 dotted line, the rope r' will run clear of the bottom side of the boom. r' represents the rope r in one of its limiting positions.

The operation of my device is as follows; Referring to Fig. 1 the line r runs from the 15 load up over the sheave 7 at the boom point thence it may, if desired, lead through the sheave 11 thence to the winding drum. But it is common practice to lead this rope from the boom point to sheave 10 thence over 20 sheave 11 to the winding drum. The stress in the part leading from the point to the sheave 10, causes the boom to swing toward the sheave 10 and this motion is controlled by the guy w . By changing the sheave 10 to 25 the outer eye bolt y and bringing the lower end of the guy w to the other side of the lighter, the boom may be caused to swing in the other direction and be controlled similarly by the guy w . Hence by changing this 30 sheave 10 and the guy w from side to side the load may be caused to swing in either direction under control. My invention bringing this part of the rope above the boom and allowing side lead enables it to run equally 35 clear when the sheave 10 is on either side. And the provision for side lead of the part of the rope leading from the boom point to the load enables a load to be dragged in from a distance to a point under the boom point and 40 then raised without the rope running off the sheave at the point and without requiring any guide outside of the block itself.

In Figs. 6 and 7, I show another form of boom point which will give the same results 45 in which I make use of two blocks instead of one. In this case the side members l , l of the frame form an extension to the boom g . There is also the topping-lift bail b , the load bail b' and the pin 1 as in the case of the other 50 boom point. The sheave 9 and 8 are held in the shells q and u by the sheaves pins 6 and 5 respectively, both shells being hung so as to swing about axes parallel to the part of the rope r , reaching between the two sheaves 55 as shown. The shell q is pivoted on the hollow pin o at one end and the fork-shaped piece s at the other. The hollow pin o is threaded into the cross piece m' and held firmly by the check nut p . The fork-shaped 60 piece s is fastened to the shell and the cylindrical stem passes through the cross member m forming a journal. The shell u is hung over the pin 4 which passes through and is held by the cross members n , n . These cross 65 members are fastened to the uprights v , v

which in turn are fastened to the frame member 1, 1. These axes above mentioned make an angle with the length of the boom, the proper angle being determined for each case separately. The rope r passes up over the 70 sheave 9, thence through the hollow pin o over the sheave 8 then to the winding drum as described. The swinging motion of the shell q allows considerable and sufficient side lead of the part of the rope r reaching to the 75 load, and the swinging motion of the shell n allows considerable side lead to the part of the rope r leading in from the end of the boom. The dotted line r'' and r''' show limiting positions of the rope r . 80

It will thus be seen that I may make use of a single sheave or block or a plurality of blocks for guiding the fall over the end of the boom but in either case the upper sheave edge must be above the line of the upper side 85 of the boom so that the fall will be clear of the boom as it is led down and the block or blocks should be so hung or pivoted that they will conform to a limited amount of side lead either above or below the end of the 90 boom. It will be seen that this arrangement of sheaves at the end of the boom is equally applicable to a single whip as described and to a tackle when the latter is used in connection with the load bail and with the fall led 95 over the end of the boom. The block will conform to the side lead in this case as well as when a single whip is used.

I claim:

1. The herein described boom point for 100 derricks having a block loosely hung or pivoted at the end of the boom so as to be capable of movement about two or more axes to conform to a limited side lead of the fall with the upper edge of the sheave above the line 105 of the upper side of the boom.

2. The herein described boom point for derricks having an extension end for the boom extending above the general line of the boom and a sheave loosely hung or pivoted 110 to said extension and disposed between the end of the same and the end of the boom so as to be capable of movement about two or more axes with the upper edge of the sheave above the line of the upper surface of the 115 boom.

3. The herein described boom point for derricks having a boom extension composed of two side plates and an end plate terminating beyond and above the center line of the boom and a block loosely hung from said end plate so as to be capable of movement about 120 two or more axes with the upper edge of its sheave above the line of the upper side of the boom.

4. The herein described boom point for derricks having a boom extension composed of two side plates and an end plate terminating beyond and above the center line of the boom, an eye bolt in said end plate and a 125 130

block hung loosely in said eye bolt having the upper edge of sheave above the line of the upper side of the boom.

5. The herein described boom point for derricks having a boom extension composed of two side plates and an end plate terminating beyond and above the center line of the boom, an eye bolt in said end plate and a

block having its two side plates united by a pin which passes loosely through said eye bolt and has a recess on its under side.

Signed by me this 20th day of Dec., 1906.

RAYMOND F. BENNETT.
